[57] CLAIM

The ornamental design for a dog house, as shown and described.

DESCRIPTION

FIG. 1 is a front elevational view of a dog house showing my new design, the rear is substantially identical to the front without the opening;

FIG. 2 is a side elevational view thereof, the opposite side is a mirror image;

FIG. 3 is a perspective view thereof;

FIG. 4 is a front elevational view of a second embodiment of FIG. 1, the rear is substantially identical to the front without the opening;

FIG. 5 is a side elevational view of FIG. 4, the opposite side is a mirror image; and,

FIG. 6 is a perspective view of FIG. 4.

The bottom of both embodiments is plain and unornamented.

The broken lines are for purposes of illustration only and form no part of the claimed design.
